UNITED STATES PATENT OFFICE

JOHN CARTMELL, OF SPOKANE, WASHINGTON, ASSIGNOR TO C. R. C. AIR CLEANER CO.,
OF SPOKANE, WASHINGTON

AIR CLEANER DEVICE

Application filed November 30, 1931. Serial No. 578,031.

My present invention relates to air cleaner devices, or more particularly to an air cleaning device that is adapted for use in connection with internal combustion engines and the like for removing dirt and dust from air prior to its entry into the engine, and is an improvement over the device disclosed in my co-pending application entitled "Air cleaners", Serial No. 511,265, and filed January 26, 1931 10 which matured to Patent 1,846,706 granted Feb. 23, 1932. Certain objects of my present invention are to provide an improved cartridge casing for retaining the main baffles together with means whereby said casing is 15 mounted in slanting disposition within the device and whereby same may be readily removed therefrom. Further objects of the invention are to provide an improved lower baffle plate for directing the upward passage 20 of the air, for preventing the suction of the engine from lifting the oil from the bottom of the device, and for regulating the amount of air passing therethrough. Still further objects are to provide a plate for the bottom 25 of the device for catching the dirt that is removed from the air by the oil and which plate may be readily lifted out for cleaning.

With the above and other objects in view which will appear as the description proceeds, the invention consists of the novel construction, adaptation, combination and arrangement of parts hereinafter described and claimed. These objects are accomplished by devices illustrated in the accompanying 35 drawings; wherein:

Figure 1 is a somewhat diagrammatic view in side elevation showing my device mounted in a forward portion of a motor vehicle and connected with the engine thereof;

Fig. 2 is a view in perspective of the air cleaner as a whole;

Fig. 3 is a view in transverse vertical section taken substantially on a broken line 3-3 45 of Fig. 2;

Fig. 4 is a detail view in perspective of the lower baffle plate;

Fig. 5 is a view in vertical section showing a fragmentary upper portion of one of the 50 main baffles;

Fig. 6 is a detail view in vertical section showing the bolt supporting means for one end of the lower baffle plate;

Fig. 7 is a detail view in transverse vertical section showing the rivet supporting means for the other end of the lower baffle plate;

Fig. 8 is a general view in longitudinal vertical section of the cleaner taken substantially on a broken line 8-8 of Fig. 2;

Fig. 9 is a view in perspective showing the retaining cartridge for the main baffle members, with parts broken away; and

Fig. 10 is a detail view in vertical section showing a supporting means for one end of the baffle retaining cartridge.

Referring to the drawings throughout which like reference numerals indicate like parts and more particularly to Fig. 1, the numeral 5 designates an ordinary internal combustion engine that is mounted in the forward portion of a motor vehicle and has the usual carburetor 6 that is connected by a flexible conduit 7 to the outlet portion 8 of the main upper casing member 9 of my device. Upon each suction stroke of the engine outside air enters said casing member through a main intake opening 10 in its end and through a plurality of smaller openings 11 in its top.

A main lower casing member 12 is detachably connected to the open bottom of said upper casing member by means of spring snap hooks 13 as most clearly shown in Fig. 8.

A plate 14 rests within said lower casing member and covers the bottom thereof. Said plate is centrally provided with an upstanding spline or flange 15 which is used as a handle in removing said plate. A pool of oil 16 is placed in the bottom of said lower casing member for reasons hereinafter set forth and said upstanding flange serves as a gauge for the depth of the oil when same is first placed within the casing.

The cartridge casing for holding the main baffle members comprises sides 17 that are held in spaced apart relation by a forward convex plate 18 and a rear concave plate 19 each riveted or otherwise secured to said sides. Both of said plates have a bead 20

formed on their upper and lower edge portions. Said cartridge is supported within the outer casing at its lower forward edge by means of a metal plate 21, curved to conform 5 to the curvature of the forward convex plate, and which plate extends entirely across and is riveted to the upper casing member 9, as at 22. Said plate 21 fits against said convex plate and its lower end engages the bead 20 thereof. A spring snap 23 is secured to the plate 21 and the lower hooked end of said snap engages under said bead thus detachably supporting the forward end of the cartridge casing. Said plate 21, as shown in detail 10 in Fig. 10, is covered with felt 24 which collects dust and prevents same from passing or entering between said plate and the convex cartridge plate.

The upper rear edge of said cartridge casing is supported by a plate 25 riveted to the top of the upper casing member 9, as at 26, and extending entirely across said upper casing member for the purpose of preventing the passage of air and dust. The lower edge 20 portion of said plate is curved inwardly to form a hook edge 27 which engages under the bead 20 formed on the upper rear edge of the concave cartridge plate 19. The supporting plates 21 and 25 are formed and positioned to support the baffle retaining cartridge in slanting disposition as clearly shown 30 in Fig. 8 of the drawings.

The main baffles, designated as a whole by the numeral 28, are curved or arcuate in cross section. Each of said baffles comprises an inner thick sheet of felt 29 which is saturated with oil and encased in a metal covering 30. Said covering extends entirely around said felt sheet and may be overlapped at its upper end as shown in detail in Fig. 5. Said metal covering is provided with a plurality of spaced apart downwardly and outwardly projecting wings 31 extending most all the way across same and which wings may be 40 stamped or punched outwardly from the covering on both sides thereof. The outer convex and concave plates 18 and 19 respectively form the outer covering portion for the end baffles and have said wings formed on their inner covering portions only. The slots 32, formed in punching out said wings, leave the inner felt sheet exposed in places for the collection of dust.

The main baffle members 28 are installed 50 within the baffle retaining cartridge casing in spaced apart relation and in parallel relation with the convex and concave outer plates 18 and 19. Arcuate passages 33 are thus formed between said baffles for the passage of air. Said baffles are preferably installed within said cartridge in a manner that they may be removed for cleaning, and arcuate slots or channels may be provided on the inside walls of the cartridge sides 17 to receive 60 the end edges of said baffles, as disclosed in my

aforesaid copending patent application, or any other means may be used for detachably installing said baffles. To further prevent any dust from passing the main baffles, a strip of felt 34 is held against the sides of the upper casing member 9 and against the outer top edges of said baffles by means of angle-iron bars 35 riveted to the sides of said upper casing member.

A lower baffle plate, designated as a whole 75 by the numeral 36 and shown in detail in Fig. 4, is mounted directly below the main baffle retaining cartridge casing as most clearly shown in Fig. 8. Said baffle plate extends transversely the full width of the lower casing member 12 and comprises a solid portion 37 which prevents the suction of the engine from lifting the oil 16, and a relatively large opening 38 with depending side flanges 39 for the passage of air. Said baffle plate has a forward upturned flange end 40 with convergent slots 41 therethrough. Said slots are slipped over the heads of bolts, as at 42 and as shown in detail in Fig. 6, for detachably supporting the forward end of said baffle plate. The rear portion of said plate may be supported by rivets 43 in the sides of the lower casing member as shown in detail in Fig. 7. An upstanding flange 44 is provided on the rear end of said baffle plate 80 and its upper edge is curved, as at 45, to fit the lower bead 20 of the concave plate 19 thus serving as an additional support for the rear end of the baffle retaining cartridge casing. Said rear flange is provided with openings 46, as shown in Fig. 8, for the passage of air, and, as shown in dotted lines in Fig. 4 at 47, a plurality of aligned punctures 90 may be provided through said flange along said dotted lines and the portions outlined by said punctures may be cut away, one at a time, to provide proper air passage in conformity with the size of the particular engine and the strength of its suction as will be understood.

In the operation of my device, each suction stroke of the engine 5 draws outside air through the openings 10 and 11. This incoming air strikes the rear concave plate 19 of the baffle retaining cartridge casing and is directed downwardly thereby to the oil pool 16. The heavier particles of dirt and dust are removed from the air by the oil pool and settle to the bottom thereof on the plate 14, as shown at 48 in Fig. 8, and may be cleaned out by removing said bottom plate. The air then passes upwardly through the opening 38 in the baffle plate 36, and then through the arcuate passages 33 between the curved main baffles 28. In these passages the air is greatly agitated by their curvature and by the projecting wings 31. These wings, due to their large number and slanting disposition, thoroughly intercept the air and collect the dust therefrom which is deposited through the 100

slots 32 on to the exposed portions of the inner felt sheets 29 which are saturated with oil thus causing the dust to readily adhere thereto. Thus it will be apparent that I have provided an effective means for removing the dust and dirt from the air prior to its passage through the carburettor 6 and entry into the engine 5.

Having thus described my invention, it being understood that minor changes in its construction and arrangement may be resorted to without departing from the scope and spirit of the invention, what I claim and desire to secure by Letters Patent of the United States is:—

1. An air cleaner device having in combination a main casing comprising detachably connected upper and lower members, air intake and outlet means for the upper casing member, a cartridge casing detachably mounted in slanting disposition within the main casing and having a convex front end plate and a concave rear end plate, a pool of oil in the bottom of the main casing, the rear concave plate arranged to form a baffle and a passage for directing incoming air downwardly against the pool of oil, a bottom plate seated in the bottom of the main casing and having a central upstanding flange, a lower baffle plate detachably mounted immediately below the cartridge casing and having a large opening for the upward passage of air, a rear upstanding flange for said baffle plate having passages for air therethrough, and a plurality of curved baffle members mounted in parallel spaced apart relation within the cartridge casing forming arcuate passages for directing air upwardly and outwardly through the outlet means.
2. An air cleaner device comprising in combination a main casing having air intake and outlet means, a cartridge casing, spring snap means for detachably supporting the lower forward edge of said cartridge casing within the main casing, plate means for supporting the upper rear edge of the cartridge casing whereby said casing is disposed in slanting disposition within the main casing, a convex front end plate and a rear concave plate for the cartridge casing, a pool of oil disposed in the bottom of the main casing, the rear concave end plate arranged to form a baffle and a passage for directing incoming air downwardly against the pool of oil, a lower baffle plate detachably mounted directly below the cartridge casing and having a large opening for upward passage of air, a rear flange for said baffle plate extending upwardly to supporting engagement with the lower rear edge of the cartridge casing, said rear flange having air passages adapted to be varied in size, a plurality of curved baffle members mounted in spaced apart relation within the cartridge casing forming arcuate air passages, and said

baffles comprising a central felt sheet encased by metal with wings punched outwardly therefrom whereby portions of the felt sheet are exposed to passing air.

In testimony whereof I affix my signature. ⁷⁰
JOHN CARTMELL.
